UNITED STATES PATENT OFFICE.

JOHN B. DOWNING, OF ORANGE, NEW JERSEY.

DESIGN FOR A COMBINED TREE STAND AND LIGHTER.

Application filed April 24, 1926. Serial No. 17,433. Term of patent 7 years.

To all whom it may concern:

Be it known that I, JOHN B. DOWNING, a citizen of the United States, residing at Orange, in the county of Essex and State of New Jersey, have invented a new and ornamental Design for a Combined Tree Stand and Lighter, of which the following is a specification, reference being had to the accompanying drawing, forming part thereof, in which—

Fig. 1 is a plan view of the combined tree stand and lighter.

Fig. 2 is an elevation of same.

I claim:—

The ornamental design for a combined tree stand and lighter as shown.

JOHN B. DOWNING.
